UNITED STATES PATENT OFFICE.

JES J. JESSEN AND JAMES H. ROSS, OF OMAHA, NEBRASKA.

BAG.

SPECIFICATION forming part of Letters Patent No. 723,282, dated March 24, 1903.

Application filed March 13, 1902. Serial No. 98,093. (No model.)

To all whom it may concern:

Be it known that we, JES J. JESSEN and JAMES H. ROSS, citizens of the United States, residing at Omaha, in the county of Douglas 5 and State of Nebraska, have invented certain new and useful Improvements in Bags; and we do hereby declare the following to be a full, clear, and exact description of the invention, such as will enable others skilled in the art to 10 which it appertains to make and use the same.

This invention relates to improvements in bags, and particularly bags which are used for containing money, such as those employed by banks, express companies, and the 15 like.

The invention has for its object the production of a bag with a seam which cannot be worked loose, thereby allowing some of the contents of the bag to be extracted with- 20 out breaking the seal at the mouth of the bag.

It has for a further object the provision of a bag with a seam having the above qualities, but which shall not be too bulky or use 25 an unnecessary amount of cloth and will be capable of being manufactured in a simple and inexpensive manner.

It consists in a bag having its edges brought together and stitched with a safety-seam, af- 30 ter which the stitched edges are folded back upon the bag and the new edges thus formed are again stitched, thus doubly securing the edges of the bag together and making it difficult for the seams to work loose or to be 35 loosened.

It further consists in certain other novel constructions, combinations, and arrangement of parts, as will be hereinafter fully described and claimed.

In the accompanying drawings, Figure 1 represents a side elevation of a bag constructed in accordance with the present invention, the first seam only in securing the edges thereof together having been taken. Fig. 2 repre- 45 sents a side elevation of the same, the second seam joining the edges of the bag having been taken. Fig. 3 represents a sectional view through the bag on the plane of line 33, Fig. 2.

The bag claimed in this application is pref- 50 erably formed of a single piece of cloth 1, folded upon itself and arranged so that the selvage edge of the goods may form the up-

per or mouth edge of the bag, and the side and bottom edges of the bag are folded in the same direction, so as to bring the cut 55 edges together, and a single seam 2 is first run around said edges, as indicated in Fig. 1. The stitched edges of the bag are then folded back upon the body portion of the bag, and a second seam 3 is run around the edges of 60 the bag between the first seam and the double edge of the material. The joined edges of the material forming the bag will thus be seen to be doubly protected, and if anything occurs to one seam the other will still 65 prevent any chance of coins or other articles within the bag passing out at such a place. The drawings necessarily show the same in a somewhat bulky form, since in order to illustrate the invention the cloth has to be given 70 considerable thickness. In use, however, the same will not be found to be exceedingly bulky and is admirably adapted for the de- 75 sired purpose. It will be observed that the first seam 2 is passed through four thicknesses of the material, and the second seam will then be passed through four thicknesses of the material except at the corners of the bag, where it will pass through eight thicknesses 80 of said bag.

The bag above described will be seen to be simple in construction, and yet the edges which have been joined by the seams, as set forth, will be found to be exceedingly strong and durable and difficult to work loose or 85 bring into a condition in which money or other articles can be extracted from the bag, a closed or covered seam being produced by the folding together of the edges of the material in the same direction, as described, whereby said 90 material must be cut away before the stitches can be approached between the edges.

Having fully described our invention, what we claim as new, and desire to secure by Letters Patent of the United States, is—

1. A bag comprising a suitable piece of folded material having its edges applied together and folded in the same direction, a seam passed through the four thicknesses of the material of the folded portion, a second 95 fold being made in the edges and a second seam passed through the four thicknesses of material of the second fold outside the first fold, 100 substantially as described.

2. A bag comprising a suitable piece of material folded upon itself with its edges in the same direction having an inner safety-seam stitched around the meeting edges thereof, a 5 second fold being formed in said edges, and a second seam passed through the second fold between the inner edge and the outer double portion of the bag, substantially as described.
3. A bag comprising a piece of suitable material folded and having its selvage edge forming the mouth of the bag, the cut edges of the material being applied together and folded 10

in the same direction, a safety-seam through the fold of the said edges, a second fold in the edges of said material, and a second seam 15 securing said fold, substantially as described.

In testimony whereof we hereunto affix our signatures in presence of two witnesses.

JES J. JESSEN.
JAMES H. ROSS.
